Primary Examiner — Michael Pratt(74) *Attorney, Agent, or Firm* — Leydig, Voit & Mayer, Ltd.(57) **CLAIM**

I claim the ornamental design for a sticker and a candle combination, as shown and described.

DESCRIPTION

FIG. 1 is an exploded perspective view of an embodiment of a sticker and a candle with indeterminate length according to the present invention.

FIG. 2 is a perspective view of the sticker and the candle of FIG. 1.

FIG. 3 is a top plan view of the sticker and the candle of FIG. 1.

FIG. 4 is an exploded front elevational view of the sticker and the candle of FIG. 1; and,

FIG. 5 is a front elevational view of the sticker and the candle of FIG. 1. The rear elevational view and the left and right side elevational views of the sticker and the candle of FIG. 1 are the same as the view of FIG. 5.

The bottom of the sticker for a candle of FIG. 1 is flat. Features illustrated in broken lines in the Figures depict environmental structure shown for illustrative purposes only and form no part of the claimed design.
